PHONOGRAPH

Heinrich F. Max Gramann, Orange, N. J., assignor
to Thomas A. Edison, Incorporated, West Orange, N. J., a corporation of New Jersey

Application August 18, 1939, Serial No. 290,740

10 Claims. (CL 74—424.8)

This invention relates to phonographs, and has especial reference to phonographs of the type wherein the movement of a sound box or other translating device relative to a record is selectively controlled by the engagement and disengagement of a feed nut with and from a feed screw, the feed nut being for example carried by a carriage which moves one of the mentioned elements. The invention is of especial value in connection with phonographs adapted for the recording, or selective recordation and reproduction, of sound, such as the commercial phonographs commonly known as "dictating machines."

In the use of phonographs of the type described it is desirable that the manipulation intended to engage the feed nut with the feed screw shall insure a complete engagement. If it fails to do this, a "slack" is left between the threads of the nut and the screw, of some length up to the spacing between successive convolutions of the thread, and the initial period of operation following the manipulation will be consumed in taking up this slack, without any actual feeding or driving of the carriage. The recordation of sound supplied to the translating device during this period will accordingly "pile up"; in the case of helical groove recording, the piling up is an incident of the initial grooving not being helical, but purely circular. In any event there may be lost the effective recordation of sound supplied during this initial period.

It is an object of my invention to provide a novel and improved structure whereby, upon manipulation intended to effect feed nut engagement with the feed screw, a complete such engagement is insured.

If during the act of engagement the nut be displaced a predetermined distance (for example equal to the spacing between thread convolutions) relative to the carriage in a direction opposite to that of driving by the feed screw, the slack may be dependably eliminated in all cases. In any individual case some portion of the displacement is absorbed in taking up the slack, while the balance may be absorbed in a permissible movement of the carriage in the direction of driving.

It is an object of my invention to provide an improved structure wherein during the engagement of the feed nut the slack will first be eliminated and the carriage thereafter subjected to a slight movement in the direction of its driving.

In arranging for the abovementioned displacement of the feed nut relative to the carriage, the feed nut may be movably or yieldably sup-

ported to the carriage. But at the completion of the manipulation intended to effect feed nut engagement, it is desirable that the nut be securely coupled to the carriage as to movement in the driving direction.

It is an object of my invention to provide an improved arrangement whereby yielding and secure relationships are obtained at the appropriate times.

It is a general object to provide a simple, effective and readily manufactured structure for carrying and controlling the feed nut.

Other and allied objects will more fully appear from the following description and the appended claims.

In the description of the invention reference is had to the accompanying drawing, of which

Figure 1 is a vertical cross-sectional view of the upper portion of a phonograph in which my invention is embodied, principally showing the translating device carriage, the feed nut supported therein, and the feed screw with which the nut is engageable;

Figure 2 is a rear elevational view of the portion of the phonograph shown in Figure 1;

Figure 3 is an enlarged horizontal cross-sectional view taken along the line 3—3 of Figure 1, showing in particular the top of the feed nut support;

Figure 4 is a bottom view of the feed nut support, showing the nut and the means through which the nut is carried by the support; and

Figure 5 is a further enlarged vertical cross-sectional view taken substantially along the line 5—5 of Figure 3.

Reference being had to Figures 1 and 2, there will be seen (in Figure 1) a record supporting device or mandrel 1, on which there is adapted to be supported a cylindrical record R (typically though not limitatively a wax record); the mandrel 1 is adapted to be rotated by means not herein necessary to show. Parallel with the mandrel are provided the front and back carriage rods 2 and 3, on which the carriage 4 is slidably mounted. The carriage may include vertical lefthand and righthand side members 4a and 4b, a top member 4c, and a sleeve 5 extending between the side members about the front carriage rod 2. Behind and parallel to the rod 2 is provided the feed screw 20, rotatable (for example simultaneously with mandrel rotation) by means not herein necessary to show. The feed nut 21 is supported in the carriage, above the feed screw 20, through mechanism hereinafter described.

In the forward portion of the carriage is car-

ried the translating device 6. While no limitation to any particular type of such device is intended, it may for example be a sound box which in its essentials is of the type disclosed in U. S. Patent No. 1,989,198, issued January 29, 1935, on application of Charles Huenlich. Thus it may include the recording stylus 7 and reproducing stylus 8, respectively carried by two circular members 9 and 10 each pivotally mounted as at the point P at the front of the device. In the carriage is carried a mechanism for selectively engaging the recording stylus, the reproducing stylus, or neither stylus with the record, to place the translating device respectively in recording, reproducing or neutral condition. Such a mechanism, itself known in the art, has been fractionally indicated herein by the illustration of a member 13 rotatably surrounding the sleeve 5 within the carriage, and by the partial illustration of lifting fingers 11 and 12, each of which is adapted for movement by the rotation of member 13 to selectively raise a respective one of the circular members 9 and 10. The angular position of member 13 about the sleeve 5 may be controlled by a lever 16 extending from that member upwardly through an elongated aperture 15 in the carriage top member 4c. When the member 13 is in its illustrated position both the circular members 9 and 10 may be in raised position, holding both the stylus 7 and 8 away from the record and thus establishing a neutral condition of the translating device. When the lever 16 is moved forwardly and the member 13 thus rotated counterclockwise (when viewed as in Figure 1) both the circular members 9 and 10 may be lowered, to result in contact of the recording stylus 7 with the record and thus the establishment of a recordation condition of the translating device. When the lever 16 is moved rearwardly and the member 13 thus rotated clockwise, the circular member 10 only may be lowered, to result in contact of the reproducing stylus 10 with the record and thus the establishment of a reproduction condition of the translating device.

It will be understood that when the mandrel and feed screw are rotated, with the feed nut in engagement with the feed screw as hereinafter more fully described, either stylus in contact with the record will traverse a spiral path thereon. If the lever 16 be adjusted for engagement of the recording stylus with the record, the translating device may cause that stylus to engrave in the record a spiral groove of depth undulating in accordance with sound or sound-representing energy supplied to the translating device (for example, through the neck 19 appearing as part of the translating device in Fig. 1). If the lever 16 be adjusted for engagement of the reproducing stylus with the record, the translating device may serve to deliver (for example, through the neck 19), sound or sound-representing energy translated from an undulating record groove being traversed by the reproducing stylus.

In addition to its control of the translating device, the lever 16 may be made to move an arm system 50 for control of the feed nut engagement—for example to cause that engagement when the translating device is conditioned for either recordation or reproduction, and to hold the nut disengaged from the feed screw when the translating device is conditioned in neutral. The same arm system may conveniently be employed to provide a detent for retaining the lever 16 in that one of its three positions to which it may at

any time be adjusted. While the manner in which it influences the feed nut is detailed hereinafter, the arm system itself may now be described.

The arm system 50 may comprise a generally vertical plate 51 extending from side to side within the carriage, and having two ears 52 extending forwardly therefrom adjacent the respective carriage side members to be pivotally mounted on a cross rod 49 which extends between the carriage side members somewhat to the rear of the sleeve 5. The lefthand portion of the plate 51 is extended downwardly from the ears 52, and from its bottom portion there is folded forwardly in a vertical plane an arm 54; this may extend to underneath the member 13 above-mentioned. The end portions of the member 13 may be provided with extensions or lugs directed downwardly and slightly rearwardly (indicated in Figure 1 by the lefthand such lug 13a), and therebetween may be secured a horizontal cross pin 48, surrounded by a roller 47. The arm 54 is biased upwardly to bear against this roller—i. e., the arm system 50 is biased clockwise (when viewed as in Figure 1) about the cross rod 49—by a strong spring 55 tensioned between the forward extremity of arm 54 and a lug 56 secured in the carriage diagonally thereabove. The top surface of the arm 54 is provided with a raised portion 58, from which camming surfaces 60 and 62 lead rearwardly and forwardly to lower surface portions 61 and 63, respectively; and a slight indentation 59 may be provided centrally of the raised portion 58. When the lever 16 is positioned for neutral adjustment of the translating device, the roller 47 may lie in the slight indentation 59 in the raised portion 58, holding the arm system 50 in the illustrated position. As the lever 16 is moved into either recordation or reproduction position (moving to the respective extremity of the aperture 15 and correspondingly rotating the member 13), the roller 47 will be rocked either rearwardly or forwardly to pass over the respective one of the camming surfaces 60 and 62 into at least substantial contact with the respective one of the lower surface portions 61 and 63—the arm system in response to its bias meanwhile executing an appreciable clockwise movement from its illustrated position.

Attention may now be directed to the feed nut and feed screw; these are particularly well seen in the enlarged Figure 5. They have been illustrated as arranged for the driving of the carriage from left to right in the phonograph—which is from right to left in the showing of Figure 5, as indicated by the arrow therein. The feed screw by way of typical example has been shown as having a single thread. The face of the feed screw exposed toward the direction in which the carriage is driven, designated as 20a, may be termed the driving face; the other face, designated as 20b, may be termed the seating face. The feed nut 21 is of approximately square plan, and its arcuate bottom surface is cut with a thread similar to that of the feed screw and adapted for engagement therewith. The face of the nut thread exposed toward the driving face 20a of the feed screw thread has been designated as 21a, and may be termed the driven face; the face exposed toward the seating face 20b of the feed screw thread has been designated as 21b, and may be termed the seating face of the nut thread. I prefer that the driving and driven faces 20a and 21a be disposed essentially at right angles to the axis of the feed screw, with the 75

seating faces 20b and 21b oblique to that axis, though unnecessary limitations in this respect are not intended.

In engaging the feed nut with the feed screw in accordance with my invention, the nut may be moved relative to the carriage, first toward the screw substantially at right angles to the screw (typically substantially parallel with the driving and driven faces 20a and 21a) until the seating faces 21b and 20b are in contact with each other (resulting in a partial nut-screw engagement), and then sidewardly, oppositely to the direction of carriage driving. During the sideward movement, which may be of predetermined or substantially predetermined distance, pressure on the nut toward and perpendicular to the screw is maintained, so that the seating face 21b of the nut will slide along the seating face 20b of the screw for whatever fraction of the inter-convolution spacing is required to bring the driving and driven faces 21a and 20b into contact with each other (completing the nut-screw engagement); and after this contact is established the residue of the sideward movement is taken up in advancing of the carriage in the driving direction. Finally the nut may be securely locked to the carriage as to sideward or driving-direction movement.

A structure according to my invention, for nut engagement in the manner outlined, is illustrated in all the figures; its details, however, are best seen in the relatively enlarged Figures 3, 4 and 5.

The feed nut 21 is immediately secured to the bottom of a nut mount 23, as by screw 22. The main part of the nut mount may be in the form of a horizontal plate. From the lefthand extremity of this plate there may be folded acutely downwardly and rightwardly a wide lug 24. From the central portion of the righthand extremity of the plate there may be folded diagonally downwardly, parallel to lug 24, a lug 25. The front and rear portions of the righthand extremity of the plate are extended somewhat beyond the central portion just mentioned; and from them there may be folded downwardly, parallel to the lugs abovementioned, the lugs 26.

The nut mount 23 is movably carried by a support 28, the main portion of which may comprise a generally horizontal plate. A wide flange 29 is turned down from the front edge of this plate, and a relatively narrower flange 30 is turned down from the rear edge; the spacing between these flanges may be such as to just freely accommodate the front-and-back dimension of the mount 23. Between these flanges, near the respective ends of the support 28, and spaced below and parallel to its main plate portion, are secured two mutually parallel thin rods 31. The main portion of the mount 23 is disposed above these rods, being adapted to rest thereon when the feed nut is disengaged from the feed screw. Then the righthand lugs 25 and 26 may be disposed on either side of, and in at least substantial contact with, the righthand rod 31, while the lefthand lug 24 is disposed in at least substantial contact with the lefthand rod 31. The mount 23 may be biased to rest on the rods 31 not only by gravity, but also by two or more springs 35 compressed between the mount 23 and the bases of upward depressions 32 in the support 28.

The front flange 29 of the support 28 is secured to the rear of the plate 51 (mentioned above as forming a part of the arm system 50), as by screws 36, and is thus rendered secure with

respect to the carriage as to horizontal movement, or movement in the driving direction. From the plate 51 the support 28 extends rearwardly so that the nut 21 lies over the feed screw 20. With the lever 16 positioned (as illustrated) for neutral condition of the translating device, the angular position of the plate 51 about the cross rod 49 is such that the nut is held slightly spaced from the feed screw (as illustrated), the mount 23 resting on rods 31 as above described. But as the lever 16 is rocked either forwardly or rearwardly, to condition the translating device for either recordation or reproduction, the clockwise rocking of the arm system above explained—and such rocking of the plate 51 in particular—lowers the support 28 substantially perpendicularly toward the feed screw. Until the nut 21 contacts the feed screw 20, the nut mount 23 also moves perpendicularly toward the screw, remaining in its illustrated position of rest on top of the rods 31 of the support.

When the seating face 21b of the nut impinges on the seating face 20b of the screw further movement of the nut and mount perpendicularly to the screw is of course prevented; the continued downward movement of the support 28 then causes the rods 31 to press downwardly against the respective lugs 24 and 25. Those rods and lugs then act as camming means for moving the mount and nut leftwardly relative to the support 28 and the carriage—the distance of such movement being predetermined, preferably at a little more than the inter-convolution spacing of the screw thread, by the length of the lugs 24 and 25 below the points at which they contact or substantially contact the rods 31 when the mount rests on those rods. In the first portion of this camming action the mount and nut will move leftwardly relative to the screw, the carriage remaining stationary; the now-further compressing springs 35 maintain the contact of the seating faces 21b and 20b of the nut and screw threads, so that this mount and nut movement is parallel with those faces, or oblique to the screw. At some intermediate instant in the camming action the driven face 21a of the nut thread will contact the driving face 20a of the screw thread, completing the nut-screw engagement; further leftward movement of mount and nut being precluded, the balance of the camming action will simply displace the rods 31 and support 28 and the carriage some slight distance rightwardly, or in the direction of driving.

After the completion of the camming action, which occurs when the rods 31 pass positions of contact with the extremities (24' and 25') of the lugs 24 and 25, the support 28 may still move further toward the screw—the range of movement of the arm system 50 being for example almost enough to bring the main portion of the support 28 into contact with the top of the nut mount 23. In this final movement of the support the nut mount (and thus the nut) may be interlocked with the support as to relative movement in the driving direction. The interlocking may be accomplished by two or more pins 33 secured in and extending downwardly from the main portion of the support 28, and fitting into respective holes 27 in the main portion of the nut mount 23 during the final support movement. The lower extremities of the pins 33 are preferably conically tapered, so that the pins will be positively guided into the holes in spite of any possible slight inaccuracy or play in the previous alignment of the mount with the support. Dur-

ing the final support movement the springs 35 are still further compressed; but however small the final spacing between the mount and support, sufficient space for each spring is provided by its respective recess 32 above mentioned. A hole 28' in the main portion of the support 28 freely admits the head of the screw 22 when the mount and support are in close relationship to each other.

- 10 In the initial portion of a reverse movement of the control lever 16—i. e., from either recordation or reproduction position to neutral position, with attendant rocking of the arm system 50 and raising of the support 28—the mount 23 will 10
- 15 remain stationary and the nut in contact with the feed screw. But when the mount and support have been unlocked from each other and the right-hand rod 31 has reached contact with the lugs 26 (at or substantially at their ends 26'), 20 that rod will cam the nut mount diagonally rightwardly and upwardly until the rods reach the bottom of the main portion of the mount. In the final portion of the movement the support and mount will of course rise together to their 25 illustrated positions.

It will be understood that the camming movement of the mount relative to the support, in both nut engagement and disengagement, is an inclined movement which is diagonally leftward-30 upward or rightward-downward—for example, substantially at right angles to the seating faces 20b and 21b of the screw and nut threads. Within the limits of their lengths, the lugs 26 and 25 (the latter supplemented by 24) act in cooperation with the rods 31 to guide the relative movement between mount and support in this direction.

While I have disclosed the feed nut engagement and disengagement as controlled by the lever which also serves to condition the translating device, this is by way of preferred example only. And it will be understood that many other details of the disclosure may be varied within wide limits without departure from the spirit or scope 45 of the invention. That scope I undertake to set forth in the appended claims.

I claim:

1. In a phonograph having translating means and record-supporting means, one of said means 50 being drivable relative to the other, and a rotatable feed screw: the combination of a feed nut engageable with said feed screw; a support through which driving movement may be imparted to said drivable means, said nut being yieldably carried by said support; means for effecting a movement of said support transversely toward said screw, whereby first to effect a partial engagement of said nut with said screw; and means for completing said engagement, including means operated by said support upon the further transverse movement thereof for moving said nut relative to said support oppositely to the driving direction.

2. In a phonograph having translating means 65 and record-supporting means, one of said means being drivable relative to the other, and a rotatable feed screw: the combination of a feed nut engageable with said feed screw, a first of the two faces of the thread of said screw being a 70 driving face adapted to drive said nut and a first of the two faces of the thread of said nut being a driven face adapted to be driven by said screw; a support through which driving movement may be imparted to said drivable means, said nut being yieldably carried by said support;

means for effecting a movement of said support transversely toward said screw, whereby first to carry the second face of said nut into engagement with the second face of said screw; and means rendered effective upon the further transverse movement of said support for moving said nut relative to said support oppositely to the driving direction, whereby to engage said driving and driven faces.

3. The combination according to claim 2, further including bias means interposed between said support and said nut for maintaining the engagement of said seating faces during said further support movement.

4. In a phonograph having translating means 15 and record-supporting means, one of said means being drivable relative to the other, and a rotatable feed screw: the combination of a feed nut engageable with said feed screw; a support through which driving movement may be im-20 parted to said drivable means, said nut being carried by said support and biased relative thereto for displacement therefrom in the direction of said screw; stop means secured to said support for establishing a normal such displacement; 25 means for effecting a movement of said support transversely toward said screw, whereby first to bring said nut into partial engagement with said screw and thereafter to reduce said displacement; and cam means, rendered effective as said 30 displacement is reduced, for completing said engagement.

5. In a phonograph having translating means and record-supporting means, one of said means being drivable relative to the other, and a rotatable feed screw: the combination of a feed nut engageable with said feed screw; a support through which driving movement may be imparted to said drivable means, said nut being carried by said support and biased relative thereto for displacement therefrom in the direction of said screw; stop means secured to said support for limiting said displacement; means for effecting a movement of said support transversely toward said screw, whereby first to bring said 45 nut into partial engagement with said screw; and cam means operative upon the further transverse movement of said support to complete said engagement, comprising said stop means and co-operating means secure with respect to said nut. 50

6. In a phonograph having translating means and record-supporting means, one of said means being drivable relative to the other, and a rotatable feed screw: the combination of a feed nut engageable with said feed screw; a support 55 through which driving movement may be imparted to said drivable means, said nut being yieldably carried by said support; means for effecting a movement of said support transversely toward said screw, whereby first to bring said 60 nut into partial engagement with said screw; means operated upon a further transverse movement of said support for moving said nut relative to said support oppositely to the driving direction, whereby to complete said engagement; 65 and means, associated with said support and with said nut and rendered effective upon the final transverse movement of said support, for interlocking said nut and support as to relative movement in the driving direction.

7. In a phonograph having translating means and record-supporting means, one of said means being drivable relative to the other, and a rotatable feed screw: the combination of a feed nut engageable with said feed screw; a mount with 75

which said nut is secure; a support through which driving movement may be imparted to said drivable means but movable relative to that means transversely of the driving direction, said 5 mount being movably carried by said support for engagement with said screw upon a transverse movement of said support; and means, provided in said support and in said mount and rendered effective in a continued transverse movement of 10 said support, for interlocking said nut and support as to relative movement in the driving direction.

8. In a phonograph having translating means and record-supporting means, one of said means being drivable relative to the other, and a rotatable feed screw: the combination of a feed nut engageable with said feed screw; a mount to which said nut is secured; a support through which driving movement may be imparted to said drivable means, said mount being yieldably carried by said support; means for effecting a movement of said support transversely toward said screw, whereby first to bring said nut into partial engagement with said screw; and cam means for causing the further transverse movement of said support to complete said engagement, comprising an inclined surface on said mount and cooperating means secured in said support.

9. In a phonograph having translating means and record-supporting means, one of said means being drivable relative to the other, and a rotata-

ble feed screw: the combination of a feed nut engageable with said feed screw; a mount to which said nut is secured; a support through which driving movement may be imparted to said drivable means, said mount being yieldably carried by said support; means for moving said support transversely toward said screw, whereby first to bring said nut into partial engagement with said screw and thereafter to cause movement of said mount relative to said support; and means, comprised in said mount and said support, for guiding the relative movement of said mount and support in a direction inclined to said screw.

10. In a phonograph having translating means and record-supporting means, one of said means being drivable relative to the other, and a rotatable feed screw: the combination of a feed nut engageable with said feed screw; a support through which driving movement may be imparted to said drivable means, including a pair of parallel 20 rods transverse to the driving direction; a mount to which said nut is secured, comprising a plate biased to rest against said rods; means for moving said support transversely of the driving direction, whereby first to bring said nut into partial engagement with said screw; and lugs extending from said plate inclinedly underneath said rods and forming therewith means for camming said mount upon further transverse support movement after said partial engagement. 30

HEINRICH F. MAX GRAMANN.
